UNITED STATES PATENT OFFICE.

ARTHUR W. SMITH, OF NEW YORK, N. Y., ASSIGNOR TO YOST WRITING MACHINE COMPANY.
OF ILION, NEW YORK, A CORPORATION OF NEW YORK.

TYPE-WRITING MACHINE.

No. 893,817.

Specification of Letters Patent.

Patented July 21, 1908.

Application filed July 1, 1905. Serial No. 267,882.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

My invention relates to inking devices for typewriting machines, and has for its main object to provide an improved ink pad case or holder and one which may be readily placed in position in the machine and removed therefrom.

To these ends the invention resides in the features of construction, combinations of devices and arrangements of parts hereinafter fully described and particularly pointed out in the claims.

In the accompanying drawings, Figure 1 is a vertical front to rear, central, sectional view of so much of a typewriting machine as is necessary to a clear understanding of the invention. Fig. 2 is a front elevation of the ink pad and the pad case or holder and showing the method of supporting the ends of the latter. Fig. 3 is an enlarged fragmentary view taken at right angles to the face of the ink pad. Fig. 4 is an enlarged transverse sectional view of the ink pad case and ink pad.

In the drawings the main frame of the machine is shown as comprising a base 1, side portions or plates 2 and a rear end 3. A suitable top plate 4, having forwardly projecting side portions 5, is secured to the side plates 2 and the rear end 3 of the frame.

A platen 6, diagrammatically shown, is arranged above the top plate and constructed to be moved from side to side thereof in a known manner during the operation of the machine. A type bar 7 is designed to coöperate with the front face of the platen 6, said type bar lying normally below said platen and being one of a segmentally arranged series each type bar 7 whereof is connected with a guide link 8 and with an actuator or driver 9. The driver 9 is pivoted at 10 in a hanger 11 secured by headed screws 12 to a segmental support 13 which is suitably mounted in the frame of the machine. Each actuator 9 is connected by a link 14 with a bell-crank lever 15, which in turn is connected by a link 16 with a key lever 17 pivoted at 18. The type bar actuating mechanism just

described forms the subject-matter of a companion application, filed May 15, 1905, Serial No. 260,441, and it is therefore not deemed necessary to set it forth in greater detail herein.

The type ends of the type bars 7 rest normally against an ink pad 19 of felt or material of similar properties and suitably impregnated with ink. The ink pad 19 is segmental in shape, as appears in Fig. 2, and rectangular in cross-section. The pad is contained in a segmental trough-like case or holder 20, preferably made of metal and formed in one piece. The ends of the case 20 are provided with laterally extending tabs or ears 21 which rests on the side portions 5 of the top plate 4 and support the pad case in the machine.

As best appears in Fig. 1, the pad case 20 is vertically disposed in the machine, and is arranged with its bottom surface at an angle to the horizontal. The front wall 20^a and the bottom 20^b of the case are guided and supported centrally of the machine by an angled metal strip or bracket 22 which is perforated to permit the passage of the screws 12 of the central hanger 11, said screws 12 securing the bracket 22 in place. The bracket 22 is provided at its upper end with arms 22^a and 22^b which form a crotch 25 in which the pad case is received, the construction being such that the lower part of the pad case is maintained in a fixed position fore and aft of the machine. The inner edges of the side portions 5 of the top plate 40 are formed at the rear with recesses or notches as indicated at 5^a (Fig. 1) and the upper parts of the pad case are received in these notches so that the ends of the pad case cannot be displaced fore and aft of the machine. Interposed between the wall 20^a of the pad case and the adjacent face of the pad is a regulator or pressure device which, as herein shown, is in the form of a segmental follower or plate 23. The regulator plate or follower 23 conforms substantially in shape to the inner face of the front wall 20^a of the pad case and is adjustable, serving in effect as a false wall or movable side of said case. The means herein shown for adjusting the plate 23 are in the form of set screws 24 which are received in threaded openings in the fixed front wall 20^a of the pad case and are shouldered off at 25, so that their inner ends 62 are of smaller diameter than the body por-

tions of the screws. The ends 26, as best appears in Fig. 4, are not threaded and are received in perforations in the inner movable wall or plate 23 against the outer face whereof the shouldered portions 25 of the regulating or adjusting screws 24 abut. I have shown five regulating screws each controlling the pressure at a different sectional portion of the ink pad, one screw being arranged near each end of the pad, one at about the center, and one about midway, between the center screw and each end screw, but, of course, the number may be varied as desired.

When the supply of ink at any part of the surface of the pad becomes such that a suitable type impression does not result from the printing operation of the types inked by that part the pad surface, the ink pad and its case may be removed from the machine and the pad may be squeezed or pressed at that part of the surface whereof is exhausted, with the result that ink from the interior or other parts of the pad is brought to the desired portion of the surface. In order to remove the pad case it is only necessary to raise all the type bars far enough from the surface of the pad to enable the case to be lifted out of the machine. It will be noted that the pad case is normally maintained in position, embraced centrally by the crotch in the bracket 22, and with the tabs or ears 21 resting against the top plate of the machine, by the weight of the pad case itself and that of the type bars, and it is only necessary to lift the type bars slightly to enable the pad case to be slipped into or out of the machine.

After the pad case has been removed from the machine the regulator plate or pressure device 23 may be forced in whole or in part towards the rear wall of the pad case by screwing in the regulating screws 24. One or all of the screws may be adjusted at any particular time as desired, according as the ink has been exhausted from one part or section only of the surface adjacent one of the screws 24 or uniformly from the entire surface. As any screw is screwed in that part of the plate or pressure device 23 controlled by it is forced towards the opposite wall of the pad case, thereby compressing the neighboring portion of the pad and forcing the ink in the interior or other part of the pad towards the desired part where said ink is available to supply the types. After regulating the ink supply as described, the pad may be restored to normal position in the machine in the manner above explained.

It will be seen that by my invention I provide in combination with an ink pad, means operative on the pad to increase the quantity of ink taken therefrom by some only of the types, or at will increasing the quantity of ink taken from the pad by some of the types and increasing to a different extent the

quantity taken by others of the types; that said means is supported by the pad case and includes devices for compressing different portions of the pad separately and for forcing ink to particular selected portions of the face of the pad; that the pad case in the present instance is convexo-concave in form; that the convex side of the case is closed and extends downward from each end of the case; that the pad has a concave face on which the types normally rest; and that the construction is such that any excessive ink which may be squeezed out of the pad will be held in the pad case and will not drop down through the machine.

Various changes may be effected in the construction and arrangements of the parts within the scope of my invention.

What I claim as new and desire to secure by Letters Patent, is:—

1. In a typewriting machine, the combination with types, of an ink pad on which the types normally rest, and means operative through the pad on the ink therein to increase the quantity of ink which may be taken from the pad by some only of the types.

2. In a typewriting machine, the combination with types, of an ink pad on which the types normally rest, and means operative through the pad on the ink therein to increase the quantity of ink which may be taken from the pad by some only of the types and to increase to a different extent the quantity of ink which may be taken by others of the types.

3. In a typewriting machine, the combination with types, of an ink pad on which the types normally rest, and means operative through different portions of the pad separately on the ink in said pad to increase the quantity of ink which may be taken from the pad by the types which rest on any of those portions of the pad on or through which said means acts.

4. In a typewriting machine, the combination with types, of an ink pad on which the types normally rest, and means operative through different portions of the pad separately on the ink in said pad and to a greater extent on or through one portion of said pad than on another to increase the quantity of ink which may be taken from the pad by the types which rest on any of those portions of the pad on or through which said means acts.

5. In a typewriting machine, the combination with the types, of an ink pad on which the types normally rest, and means operative on the pad to increase the quantity of ink which may be taken therefrom by some only of the types, said means including devices for compressing different portions of the pad separately.

6. In a typewriting machine, the combination with the types, of an ink pad on which

the types normally rest, and means operative on the pad to increase the quantity of ink which may be taken therefrom by some of the types, and to increase to a different extent 5 the quantity which may be taken by others of the types, said means including devices for compressing different portions of the pad separately.

7. In a typewriting machine, the combination with the types, of an ink pad on which the types normally rest, and means operative on the pad to increase the quantity of ink which may be taken therefrom by some only of the types, said means including devices 15 for forcing ink to a particular part alone of the face of the pad.

8. In a typewriting machine, the combination with the types, of an ink pad case, an ink-pad on which the types normally rest, 20 said pad being confined in the case, and means operative on the pad to increase the quantity of ink which may be taken therefrom by some only of the types, said means being supported by the case.

9. In a typewriting machine, the combination with the types, of an ink pad case, an ink pad on which the types normally rest, 25 said pad being confined in the case, and means operative on the pad to increase the quantity of ink which may be taken therefrom by some only of the types, said means being supported by the case and including devices for compressing different portions of the pad separately.

10. In a typewriting machine, the combination with the types, of an ink pad case, an ink pad on which the types normally rest, 30 said pad being confined in the case, and means operative on the pad to increase the quantity of ink which may be taken therefrom by some only of the types, said means being supported by the case and including devices for forcing ink to a particular part alone of the face of the pad.

11. In a typewriting machine, the combination with the types, of an ink pad case, an ink pad on which the types normally rest, 35 said pad being confined in the case, and means operative on the pad to increase the quantity of ink which may be taken therefrom by some only of the types, said means including a follower contained in the case and screws inserted in the case and bearing against the follower.

12. In a typewriting machine, the combination with the types, of a convexo-concave ink-pad case, an ink pad having a concave face on which the types normally rest, said pad being confined in the case, and means operative on the pad to increase the quantity of ink which may be taken therefrom by some only of the types, said means being supported by the case.

13. In a typewriting machine, the combination with the types, of a convexo-concave

ink-pad case, an ink-pad having a concave face on which the types normally rest, said pad being confined in the case, and means operative on the pad to increase the quantity of ink which may be taken therefrom by 70 some only of the types, said means being supported by the case and including devices for compressing different portions of the pad separately.

14. In a typewriting machine, the combination with the types, of a convexo-concave ink pad case, an ink-pad having a concave face on which the types normally rest, said pad being confined in the case, and means operative on the pad to increase the quantity of ink which may be taken therefrom by 75 some only of the types, said means including a follower contained in the case and screws inserted in the case and bearing against the follower.

15. In a typewriting machine, the combination with the types, of a segmental ink-pad case, its convex side being closed and extending downward from each end of the case, an ink-pad having a concave face on 80 which the types normally rest, said pad being confined in the case, and means operative on the pad to increase the quantity of ink which may be taken therefrom by some 85 only of the types, said means being supported by the case.

16. In a typewriting machine, the combination with the types, of a segmental ink-pad case, its convex side being closed and extending downward from each end of the case, an ink-pad having a concave face on 90 which the types normally rest, said pad being confined in the case, and means operative on the pad to increase the quantity of ink which may be taken therefrom by some 95 only of the types, said means being supported by the case and including devices for compressing different portions of the pad.

17. In a typewriting machine, the combination with the types, of a segmental ink-pad case, its convex side being closed and extending downward from each end of the case, an ink pad having a concave face on 100 which the types normally rest, said pad being confined in the case, and means operative on the pad to increase the quantity of ink which may be taken therefrom by some 105 only of the types, said means being supported by the case and including devices for compressing different portions of the pad.

18. In a typewriting machine, the combination with the types, of a segmental ink-pad case, its convex side being closed and 110 extending downward from each end of the case, an ink pad having a concave face on which the types normally rest, said pad being confined in the case, and means operative on the pad to increase the quantity of ink which may be taken therefrom by some 115 only of the types, said means including a follower contained in the case and screws 120 inserted in the case and bearing against the follower.

19. In a typewriting machine, the combination with the types, of a segmental ink-pad case, its convex side being closed and 125 extending downward from each end of the case, an ink pad having a concave face on which the types normally rest, said pad being confined in the case, and means operative on the pad to increase the quantity of 130

ink which may be taken therefrom by some only of the types, said means comprising a segmental plate or follower, and a plurality of adjusting screws carried by the case and bearing against the segmental plate, said screws being arranged at intervals lengthwise of the case.

19. In a typewriting machine, the combination of a segmental ink pad case having 10 end tabs or supports, and a bracket fixed in the machine and adapted to guide and support the central part of said ink pad case, said pad case being loosely mounted in the machine.

15 20. In a front-strike typewriting machine, the combination of a segmental ink pad case having end tabs which rest against the top plate of the machine, and a bracket fixed in

the machine and adapted to guide and support the central portion of said pad case, the 20 latter being loosely mounted in the machine.

21. In a front-strike typewriting machine, the combination of a segmental ink pad case having end tabs which rest against the top plate of the machine, and a bracket formed 25 with a crotch adapted to receive the central portion of said pad case.

Signed at the borough of Manhattan, city of New York, in the county of New York, and State of New York, this 30th day of 30 June A. D. 1905.

ARTHUR W. SMITH.
